UNITED STATES PATENT OFFICE.

FRANK C. LAME, OF NEW YORK, N. Y.

NUMBER-LANTERN FOR AUTOMOBILES.

No. 873,316.

Specification of Letters Patent.

Patented Dec. 10, 1907.

Application filed May 3, 1907. Serial No. 371,720.

To all whom it may concern:

Be it known that I, FRANK C. LAME, a citizen of the United States, residing at New York city, in the county of New York and State of New York, have invented certain new and useful Improvements in Number-Lanterns for Automobiles, of which the following is a specification.

My invention relates to lamps and particularly to a reversible lamp or lantern for carrying and displaying the license numbers of automobiles or like vehicles.

One object of my invention is to provide a lantern of this character wherein the numbers shall be displayed upon glass or other transparent slides and illuminated from the interior, thus providing a number carrier which shall be as readable by night as by day.

20 A further object is to provide a number-displaying lantern of this character capable of carrying two different license numbers, either of which may be displayed at pleasure.

25 A further object is to so construct said lamp that it shall be capable of attachment to any portion of an automobile, and may be easily adjusted to suit various conditions of situation.

30 My invention consists in the arrangement of parts and details of construction which are shown in the accompanying drawings and particularly set forth in the claims appended to this description.

35 In the said drawing, Figure 1 is a front view of the lantern. Fig. 2 is a longitudinal section. Fig. 3 is a transverse section on line $x-x$, Fig. 2, and Fig. 4 is a detail in perspective.

40 Like reference characters in all the figures indicate like parts.

The casing of my lantern may be of any desired shape adapted to the purpose of displaying a series of numerals, but I have shown it as rectangular, having a bottom 45 plate 2, a top plate 3, and ends 4. Preferably this casing is of sheet metal.

The front and rear faces of the lantern are composed of grooved frames 5 hinged to the casing either at the top, bottom or ends. 50 I have shown them as hinged to the top plate 3 of the casing as at 3', and the bottom plate 2 as being provided with catches 2' for engagement with the lower margins of the frames, which thus form doors capable of 55 being opened to get at the lamps inside. The frames 5 have each two grooves or

recesses on their inside edges, the innermost groove 6' being for the reception of a glass slip 6, and the outermost 7' adapted to receive a solid metal backing plate. 60

The glass slip 6 is provided with the license number displayed thereon in any desired manner, preferably the numbers being transparent on a ground of opaque or dark colored glass. In place of the glass 65 slip with the numbers transparent thereon, it will be obvious that I may use a metal plate having the numbers cut out, so that the light may shine through. Preferably too, the frame 5 is open at one end opposite 70 to groove 6' to permit the insertion of the glass into the groove, an opening at the top not being advisable for fear of the entrance of water.

The groove 7' is extended out through the 75 top edge of frame 5 for the removal and insertion of the backing plate 7. The bottom piece of the frame is perforated as at 7" to permit the escape of any water which may gather in the groove or behind the plate 7. 80

The plate 7 is solid and is intended not only to shut off the light emanating from the lantern on the side on which it is placed, but also to protect the glass from jars and from stones which may be thrown up against it. 85 It is provided with a spring 7' on its front to minimize any shock. It extends above the lantern and inward to form a wind shield for the chimneys 9.

8 designates a lamp reservoir of any character suitable, which is adapted to be contained within the casing, and 8' 8' are the lamp burners usual to vehicle lamps. The bottom of the reservoir is provided with the downwardly projecting hub 8" which is 90 adapted to fit into a socket 2" in the bottom of the casing. This prevents any lateral oscillation of the reservoir within the casing, while the pivoted latches 4' prevent any horizontal motion. 100

Located above the burners 8' are the chimneys 9. These consist of an inner tube 9' perforated or open at its top, and an outer surrounding tube 9" closed at its top but perforated on the sides. This arrangement 105 prevents the draft from blowing down into the lantern and blowing out the lights. As before stated, the extension of plate 7 also acts to deflect the wind which would otherwise strike the chimneys during the rapid 110 passage of the vehicle.

It is an object of my invention to provide

a lantern capable of displaying either one or a plurality of number-plates or slides and to that end I provide my lantern with means whereby it may be rotated in a horizontal 5 plane to bring either number to the front. This I accomplish by swiveling the lantern to its support and providing a clamping means for holding it in position where set. It is also very necessary that the lantern should 10 be adapted to be applied to a variety of places and hence that the lantern and its support should be capable of being set at various angles to each other.

In detail as I have embodied my invention, 15 I provide a pillar or supporting rod 10 which at its lower end is pivotally connected to a strap plate or iron 12 as later described. The lower end of the pillar is bifurcated as at 10', in which is received the stem of a headed bolt 11. A pivot pin 11' connects the stem of the bolt to the pillar. A strap iron 12 is riveted to the top of the lantern and through an opening in the top of this strap iron passes the shank of bolt 11, the head of the bolt engaging with the iron, thus forming a swivel 20 permitting the lantern to be rotated in relation to the pillar 10 or to be turned on pivot pin 11' to any angle with the pillar. The sides of the pillar 10 at its lower end are flat 25 to form a bearing for plates 13, 13, whose lower edges bear against the upper face of strap iron 12. These plates are either made in one piece with the strap iron or separate. They are perforated as shown at 13' in the 30 arc of a circle, and these perforations align with a hole through the pillar 10. A bolt 14 passes through the two plates and the pillar, thus holding the pillar set at any desired angle with the strap iron 12. The end of the 35 bolt is shown as having a pivoted latch but it is obvious that other means may be used to prevent the displacement of the bolt. The upper end of pillar 10 is the same in construction as the lower end and is attached to 40 the strap iron 15 in the same manner.

16 designates the headed bolt, 16' the pivot pin of the bolt, and 17 17 indicate the two side plates, and 17' the bolt.

In Figs. 1, 2 and 3 I have shown the upper 50 strap iron 15 as attached by screws 18 to any desired parts of the body of the vehicle, but in place of these screws—where it is desired to attach the lantern to the axle of the vehicle—, I may use U-shaped bolts 15' whose 55 ends pass through the strap iron and around the axle, and are clamped up tight thereto by the usual nuts.

The purpose of the swiveled and pivoted lantern and pillar is to permit the lantern to 60 be attached to any desired portion of the under body or to the axle, and the lamp set at the angle to properly display the numerals thereon. Such adjustments also permit the lantern to be readily moved out from the vehicle body for cleaning or moved away from 65

the body so that it may be turned horizontally to display either one or the other of the faces.

When it is desired to change the face of the lantern, it is only necessary to take out bolt 70 11' or when the lantern may be removed. The plate 7 is then inserted into groove 7' thus protecting the rear face of the lantern and providing a wind break as before described. 75

It will be seen from this description that my construction provides a lantern capable of carrying the license numbers of two different States, of quick adjustment to display either of these numbers, and which may be 80 attached to any portion of the vehicle.

Having described my invention what I claim is:

1. In a license number display lantern for automobiles, a casing, a plurality of number- 85 carrying translucent slides for the sides of said casing, a lamp within the casing, and a support for said casing having an engagement with the casing for movement in horizontal and vertical planes. 90

2. In a license number display lantern for automobiles, a casing, a plurality of number- carrying translucent slides for the sides of said casing, a lamp within the casing, and a support for said casing having swiveled engagement with the casing for rotation in a horizontal plane, and pivotal engagement with the casing for movement in a vertical plane. 95

3. In a license number display lantern for 100 automobiles, a casing, a plurality of number- carrying translucent slides for the sides of said casing, a lamp within the casing, a perforated strap engaging with the top of the casing, a support whose end is provided with 105 a swivel engagement with said strap and clamping means for holding the support set in any relative position to the said casing.

4. In a license number display lantern for 110 automobiles, a casing, a plurality of number- carrying translucent slides for the sides of said casing, a lamp within the casing, a support, side pieces upwardly extending from the lamp casing engaging with the sides of the support, and a detachable bolt passing 115 through the said side pieces and the support.

5. In a license number display lantern for automobiles, a casing, a plurality of number- carrying translucent slides for sides of said casing, a lamp within the casing, a support, 120 side pieces upwardly extending from the lamp casing and perforated in the arc of a circle engaging with the sides of the support, and a detachable bolt adapted to pass through the perforations of said side pieces 125 and the support.

6. In a license number display lantern for 130 automobiles, a casing, a plurality of number- carrying translucent slides for the sides of said casing, a lamp within the casing, a sup-

port having a swiveled engagement at its lower end with the upper side of the casing, side pieces upwardly extending from the lamp casing and perforated in the arc of a circle engaging with the sides of the support, and a detachable bolt adapted to pass through the perforations of said side pieces and the support.

7. In a license number display lantern for automobiles, a casing, a plurality of number-carrying translucent slides for the sides of said casing, a lamp within the casing, a support having a pivotal engagement at its lower end with the lamp casing for rotation in a horizontal plane, and carrying at its upper end means for attachment to a vehicle, said support being swiveled at its upper end to said attachment and having pivotal engagement therewith for movement in a vertical plane.

8. In a license number display lantern for automobiles, a casing having glass-inclosing frames on a plurality of its sides, each of said frames having double grooves, an inside groove adapted to hold a translucent slide, an outside groove for supporting a backing piece, and an opaque backing piece adapted to be inserted in any one of said outside grooves.

30 9. In a license number display lantern for automobiles, a casing, a plurality of number-carrying translucent slides for the sides of

said casing, a lamp within the casing, a support for said casing having an engagement with the casing for a movement in a horizontal plane, a chimney located above the lamp and projecting above the top of the casing, a removable wind guard adapted to be attached to either side of said lantern and projecting above the said chimney to shield the same.

10. In a license number display lantern for automobiles, a casing having glass-inclosing frames on two or more of its sides, each of said frames having double grooves, an inside groove adapted to hold a translucent slide, an outside groove open at its top for supporting a backing piece, a lamp within said casing, chimneys projecting above the top of the casing, and an opaque backing piece adapted to be inserted in any one of said outside grooves, and projecting above the top of the lantern to the height of the said chimneys, said backing piece being provided with outwardly projecting springs.

In testimony whereof, I have signed my name to this specification in the presence of two subscribing witnesses, this 7th day of March, 1907.

FRANK C. LAME.
